CLAIM

The ornamental design for a portion of a gaming input device having illuminated region, as shown and described.

DESCRIPTION

FIG. 1 is a front perspective view of a portion of a gaming input device having illuminated region showing our new design;

FIG. 2 is a top view thereof;

FIG. 3 is a left view thereof;

FIG. 4 is a right side view thereof;

FIG. 5 is a front side view thereof;

FIG. 6 is a rear view thereof; and,

FIG. 7 is a bottom view thereof.

The broken line showing of various regions, including the unshaded areas therein, is for illustrative purposes and forms no part of the claimed design. The difference in shading in FIGS. 1 and 2 indicates a contrast of appearance between illuminated and unilluminated regions, and does not depict any particular color, texture, or material.
